UNITED STATES PATENT OFFICE.

HERMAN RICHARD BOESH, OF NEW YORK, N. Y.

CLEANING ATTACHMENT FOR FIRE TUBULAR BOILERS.

1,164,914.

Specification of Letters Patent. Patented Dec. 21, 1915.

Application filed September 20, 1915. Serial No. 51,717.

To all whom it may concern:

Be it known that I, HERMAN RICHARD BOESH, a citizen of the United States, residing at New York city, in the county of New York and State of New York, have invented certain new and useful Improvements in Cleaning Attachments for Fire Tubular Boilers; and I do hereby declare the following to be a full, clear, and exact 5 description of the invention, such as will enable others skilled in the art to which it appertains to make and use the same.

This invention relates to fire tubular boilers, and has for its object to provide means 10 for cleaning out the back connections of said boilers in a manner comparatively inexpensive to provide, and one which will enable the boilers to be cleaned more efficiently than has been heretofore proposed.

With these and other objects in view the invention consists in the novel details of construction and combinations of parts more fully hereinafter disclosed and particularly 15 pointed out in the claims.

Referring to the accompanying drawings 20 forming a part of this specification in which like numerals designate like parts in all the views—Figure 1 is a diagrammatic longitudinal sectional view of a boiler provided 25 with my improvement; Fig. 2 is a transverse sectional view of the parts shown in Fig. 1; and Fig. 3 is a diagrammatic elevational view of the boiler shown in Fig. 1 illustrating 30 my improvement.

1 indicates any suitable shell for a fire tubular boiler, 2 the water space of the same, 3 the tubes leading from the back connection 4 to the stack 5, 6 the grates and 7 the ash pit. Any suitable bridge wall 8 may 35 be provided, and any suitable closure 9 for the furnace and any suitable closure 10 for the ash pit may also be provided.

It is well known that in the operation 40 of fire tubular or Scotch boilers, the tubes often get clogged up with solid material of the nature of a slag, or cinders, and at present there is no means in use known to me whereby these tubes can be effectually cleaned except by drawing the fire, letting 45 the boiler cool down, and sending a man in through the furnace portion of the boiler to chisel out and to dislodge with a pick the said solid material. This procedure invariably results in vexatious and costly delays 50 and also to injuries to the back plate connections and to the joints between said plate

and tubes. These injuries are of course aggravated owing to the great disadvantages under which the man of necessity must work. I avoid these objections, in the present invention, by providing a man hole 11 at the side of the boiler opposite the back connection 4, and by effectually closing the said man hole with a cover such as 12 detachably secured by any suitable fastenings 55 as illustrated. The said man hole cover 12 of course is provided with suitable packings such as the asbestos ring 13 and is otherwise made gas tight. The man hole 13 is preferably of such dimensions as will readily 60 accommodate the entrance of a man and will also afford him sufficient space to conveniently work at the rear ends 15 of the tubes 65 3. In the instance of a small fire tubular boiler such as that shown the walls of said 70 hole or passage 11 may be conveniently made flush with or tangential to the circle inclosing the tubes 3 as illustrated, and it is preferred that the hole 11 at its lower circumference be substantially flush with the bottom 75 16 of the back connection 4 in order that the ashes and other material may be readily scraped out. In other words by 80 locating the passage 11 so that it is substantially flush with the bottom of the ash pit 85 a man can readily enter the back connection with a shovel or rake and can readily clean out the material which is not caught in the tubes, while he is still on the outside of the 90 boiler. When the back connection is thus 95 thoroughly cleaned out it is then a comparatively easy matter to enter the said back connection with the additional space afforded by the passage 11 and to thereupon clean the tubes as has been heretofore done without working at the great disadvantage that is now encountered and also without incurring the great risks of injuring the connections between the tubes and their plates.

A very decided advantage of this invention resides in the fact that a boiler of this character can be readily cleaned at sea, and thereby avoid the necessity of bringing the ship into port. A further advantage resides in the fact that the tubes may thus be cleaned as often as desired, and thereby greatly enhance the efficiency of the boiler with a corresponding saving in fuel. At present it is customary to run a brush through the tubes about every two weeks in 100 order to clean out the soot and other material which collects therein, but in the use of 105 110

such brushes the soot and other material falls in the back connection 4 and occupies the space in the bridge wall 8 whereupon it again soon finds its way into the lowermost tubes, thus clogging them up again.

Of course it is obvious that this invention is adapted for boilers having a plurality of furnaces, as well as to boilers having only a single furnace. It is further obvious that this invention is applicable to all fire tubular boilers wherein the back connection is between the fire wall or bridge and the ends of the tubes, and wherein the said tubes are liable to be clogged by solid material collecting therein.

What I claim is:

1. In a fire tubular boiler, the combination of a plurality of tubes; a furnace; a bridge wall; a cylindrical back connection between said tube and bridge wall; walls constituting a passage leading to the outside of the boiler extending at right angles to

the axis of the boiler, and flush with the top and bottom of said back connection; and a closure for said passage, substantially as described.

2. In a fire tubular boiler, the combination of a plurality of tubes; a furnace; a bridge wall; a back connection between said tube and bridge wall; walls constituting a passage leading from the side of said back connection to the outside of the boiler extending at an angle to the axis of the boiler, said passage being sufficiently large to admit a man into said back connection; and a closure for said passage, substantially as described.

In testimony whereof I affix my signature, in presence of two witnesses.

HERMAN RICHARD BOESH.

Witnesses:

RICHARD J. DELANEY,
PETER J. BAUMAN.
